UNITED STATES PATENT OFFICE

JONAS G. JOHNSON, OF BALTIMORE, MARYLAND

DESIGN FOR A FIREPLACE

Application filed November 21, 1929. Serial No. 33,520. Term of patent 14 years.

To all whom it may concern:

Be it known that I, JONAS G. JOHNSON, a citizen of the United States, residing at the city of Baltimore, and State of Maryland, have invented a new, original, and ornamental Design for a Fireplace, of which the following is a specification, reference being had to the accompanying drawing, forming part thereof.

The figure is a perspective view of a fireplace showing my new design.

I claim:

The ornamental design for a fireplace as shown.

JONAS G. JOHNSON.
